UNITED STATES PATENT OFFICE.

ROBERT L. SHEETZ, OF SIOUX CITY, IOWA.

ACTUATING MECHANISM FOR OPENING VAULT DOORS.

Application filed April 23, 1924. Serial No. 708,418.

To all whom it may concern:

Be it known that I, ROBERT L. SHEETZ, a citizen of the United States, and a resident of Sioux City, in the county of Woodbury 5 and State of Iowa, have invented certain new and useful Improvements in Actuating Mechanism for Opening Vault Doors, of which the following is a specification.

My invention relates to vault doors, particularly of the type employing the pressure-bar system for forcing the door into place in the door casing, and has for its object to provide means of simple, novel and inexpensive construction, whereby the pressure-bar actuating-mechanism may be operated from within the vault.

It is my purpose to provide means whereby a banker or a bank employee, who has become locked within a vault by a bank robber, 20 may extricate himself from the vault.

A further object of my invention is to provide such means in the form of an attachment which may be readily secured to the inside of a vault door and connected with the pressure-bar actuating-mechanism with the 25 fewest changes in the latter structure.

Another object is to provide such an attachment which may be adapted to various makes of vault doors wherein the arrangement 30 of the pressure-bar actuating-mechanism with relation to the combination lock may be different.

More specifically, it is my purpose to provide an attachment which may be used either 35 where the combination lock registers with the pressure-bar hand-wheel shaft, and thus prevents such shaft being extended through the vault door, or where it does not, the parts being such that those used in the latter case 40 may be used also in the former with the addition of several other parts.

With these and other objects in view, my invention consists in the construction, arrangement and combination of the various 45 parts of my device, whereby the objects contemplated are attained, as hereinafter more fully set forth, pointed out in my claims, and illustrated in the accompanying drawings, in which:

50 Fig. 1 is an elevation of a vault door, together with its casing, illustrating the pressure-bar system.

Fig. 2 is a sectional view of a portion of the same with my invention attached, taken 55 on the line 2-2 of Fig. 1.

Fig. 3 is a similar view showing the at-

achment as used where the combination lock of the vault door covers the end of the pressure-bar hand-wheel shaft.

Before proceeding to describe in detail my 60 invention, I will attempt to set forth the problem which it is intended to remedy.

In most banks the door to the safety deposit vault is of such size and weight that it would be impossible to swing it closed 65 into the casing without the aid of mechanical devices of some kind. The doors are made to fit very closely within their casings in order that the possibility of introducing explosive materials or tools may be minimized. 70 It has therefore been found necessary to provide mechanical means for forcing the door closed, and this means I have shown in Fig. 1 of the drawings herewith.

The vault door, 10, is hinged at 11 to the 75 swinging yoke, 12, which in turn is hinged at 13 to the casing, 14, or to the wall of the building wherein the vault is built. On the door are suitably mounted in bearings the shaft, 15, on the ends of which are cams 80 which coact with the bearing members, 16, and which, when rotated therein, will force the door, 10, inwardly into the casing. In order to rotate the shafts, 15, the vertical shaft, 16^a, is provided which drives the 85 shafts, 15, through the medium of the gears, 17. In order to drive the shaft, 16, the hand-wheel shaft, 18, is provided, suitably journaled in the casing, 19, fixed to the vault door, and having thereon the worm, 20, in 90 mesh with the worm-wheel, 21, on the shaft, 16. The shaft, 18, ordinarily extends to a point where it is about flush with the outer surface of the vault door, 10, but does not extend into the door.

From the foregoing description it will be seen that a bank robber may force a person to enter the vault, and by actuating the pressure-bar system effectively lock the door in place so that it is impossible for the person within to effect an escape.

During recent years daylight robberies have become much more frequent than in former times. This may be due to the fact that it is easier to escape undetected after 105 having gotten away from the bank itself in the daytime, when the streets are swarming with people, than it is at night. It is, however, a fact that such robberies have become much more frequent than formerly. In 110 order to complete such a robbery, it is necessary that the employees of the bank be taken

care of in some way so they will not give the alarm when the robbers flee. The average criminal hesitates to inflict any unnecessary injury upon those with whom he comes into contact, and the most convenient and effective method of eliminating trouble from the employees is to lock them up within the vault.

Where the pressure-bar system is not in use it is possible for the prisoners to escape by removing the combination lock, which is screwed to the back of the vault door by means of screws which are removable from within, and then rotating the combination disks to position where the locking bolt may be withdrawn, and the locking bars retracted in order to unlock the door. However, if the pressure-bar system is installed on the door, it will prevent the door being opened.

I have been engaged for some time as a salesman of protective devices for vault doors, and from my experience have found that on the average six people have been locked up at a time within a vault where such a robbery has occurred. The average vault does not contain much over two thousand cubic feet of air, and it is known that the average person consumes about three hundred cubic feet of air per hour. Thus it will be seen from this that in such a vault the oxygen would be about exhausted at the end of an hour where six people have been imprisoned therein.

The arrangements of the various parts of the vault doors differ in various makes. In some cases the shaft, 18, is removed considerably from the combination lock, 22, and in other cases it is directly opposite the combination lock on the other side of the door.

It is my purpose to provide a simple attachment which may be used in either case and which may be connected to the shaft, 18, in order that the shaft, 18, may be rotated from the inside of the door. My invention includes a shank, 23, on the end of which is a socket, 24, having a square opening therein of sufficient size that it will receive the ordinary shaft, 18, which is squared for the purpose. In order to accomplish this, the casing, 19, is loosened and moved outwardly away from the vault door, the slot, 19^a, allowing such movement. The shank, 23, is rotatably mounted in a bracket, 25, and secured therein by means of a collar, 26. The socket, 24, forms a shoulder, which together with the collar, 26, secures the shank, 23, against longitudinal movement relative to the bracket, 25. In many cases the collar, 26, may be dispensed with.

On the end of the shank, 23, is a hand-wheel, 27. In the ordinary installation an opening, 28, is cut in the door, 10, so as to register with the shaft, 18. The socket, 24,

is then inserted through the opening, 28, and attached to the end of the shaft, 18, by means of a hollow headed set screw, 29, or taper pin.

Where the combination lock, 22, obstructs the end of the shaft, 18, as shown in Fig. 3, the spur gears, 30 and 31, are provided, one of which is attached to the end of the shaft, 18, by means of the elongated collar, 33, and the other end of which is attached to the shank, 23. In this case, two depressions, 28^a and 28^b, are cut in the door from opposite sides, as shown, which overlap. The depression, 28^a receives the gear, 30, and the depression, 28^b receives the gear, 31. It will be seen that the gears are thus held against longitudinal movement. At the same time, the door is not cut entirely through at one spot, and protection against fire is thus increased.

It will be seen that in this case, as in the other case, the attaching is done entirely on the inside without disturbing the mechanism on the outside of the door. The same parts are used in each case with the addition of the spur gears where the combination lock, 22, has to be evaded.

Some changes may be made in the construction and arrangement of the parts of my invention without departing from the real spirit and purpose of my invention, and it is my intention to cover by my claims, any modified forms of structure or use of mechanical equivalents, which may be reasonably included within their scope.

I claim as my invention:

1. In a device of the class described, in combination with a vault door having a horizontal pressure-bar actuating-shaft with its end terminating at the outside surface of the door, a shank, a socket on the shank adapted to be extended through a suitable opening in the door and to receive the end of the pressure-bar actuating-shaft, and a bracket for supporting the shank on the interior of the vault door.

2. In combination with a vault door having a pressure bar actuating shaft with its end terminating at the outer surface of the door, a permanent attachment for actuating the said shaft comprising a bracket, a shank journaled therein, a socket on the shank having a shoulder engaging said bracket, a collar on the shank engaging the other side of said bracket so as to maintain the shank in fixed longitudinal position relative to the bracket, a handle on the shank, the socket being extended through an opening in the door and receiving the end of the pressure bar actuating shaft.

Signed at Sioux City, in the county of Woodbury and State of Iowa, this 2nd day of April, 1924.

ROBERT L. SHEETZ.
